UNITED STATES PATENT OFFICE.

HARRY BRIDGMAN SMITH, OF BROOKLYN, NEW YORK, ASSIGNOR TO LIGHTSHIP CLOTH BOARD CORPORATION, OF BROOKLYN, NEW YORK, A CORPORATION OF NEW YORK.

CLOTH BOARD AND SIMILAR ARTICLE.

Application filed October 18, 1923. Serial No. 669,387.

To all whom it may concern:

Be it known that I, HARRY BRIDGMAN SMITH, a citizen of the United States, and resident of Brooklyn, in the county of Kings 5 and State of New York, have invented certain new and useful Improvements in Cloth Boards and Similar Articles, of which the following is a specification.

My invention relates to cloth boards and 10 similar articles, usually employed as a center upon which a bolt of fabric is wound, or for similar purposes.

These cloth boards are used in immense numbers and it is a principal object of the 15 present invention to greatly reduce the cost of such articles so that in the aggregate an immense saving is effected.

Another object is to provide a cloth board of light weight, which is at the same time 20 very stiff and strong although usually moderately resilient or flexible.

A further object is to provide a cloth board embodying some or all of the advantages above mentioned and which has a satisfactorily smooth surface or "finish" or 25 more particularly stated, one in which the broad sides are smoothly surfaced and the longitudinal edges or corners are smoothly surfaced and rounded so that there is no 30 possibility of injury, even to delicate fabrics which may be wound upon the board.

A very important object of the invention is to provide a cloth board of such material and structure that it can be produced by 35 what I call a continuous process, in which the different materials are advanced in continuous web form, brought together to form a continuous assembly, and then severed transversely to produce the individual cloth 40 boards. While the method is not claimed as a part of the present invention, it is, nevertheless, exceedingly important to so design the cloth board that it can be produced by such a continuous method, since immense 45 economy is afforded, not only by the relatively inexpensive materials employed, but by the great speed of production secured by the stated method, and which provides an immense saving as compared with hand 50 labor, which has been required in the past, largely or entirely, for the production of cloth boards of this class.

By study, experiments and practical tests I have discovered that the foregoing and 55 other objects and advantages may be at-

tained by constructing the cloth board of fibrous sheet material, preferably a material of the class generally designated as cardboard, consisting of a core or filler formed of one or more layers or sheets of fibrous sheet material, such as cardboard of substantial thickness and stiffness, these being adhesively secured together when more than one layer is used, the filler being usually of rectangular outline, of substantial length 60 and width, and the thickness usually being much less than the width of the filler structure, the filler being enclosed in a cover or envelope of suitable fibrous sheet material, usually pulp-board or cardboard of substantial thickness and strength, although in many cases thinner than the core material, this cover sheet being much wider than the filler strip or strips, and folded and adhesively secured about the filler, so that the envelope covers the broad sides and the longitudinal edges and corners of the filler and presents a perfectly smooth external surface, the edges or corners being usually more or less rounded to avoid sharp edges. 65 When the filler consists of more than one ply of material, the respective plies or layers are firmly secured together by adhesive which usually extends throughout the contacting surfaces, and the cover is also secured to the filler by adhesive over substantially the entire contacting surfaces of respective materials. In this way the completed article is practically solid or unitary, and is very stiff and strong and resistant 70 to torsional and bending strains, both longitudinally and transversely of the board. The cover material, which is, in certain preferred cases, substantially as thick as the filler and may be of similar or identical 75 material, and which therefore has very substantial thickness, stiffness and tensile strength, not only provides a smooth outer covering for the completed board, which prevents injury to any kind of fabrics which 80 may be wound upon it, but it very materially strengthens and reinforces the filler against all distortion or strains above referred to, and this result is produced not only by the thickness and stiffness of the cover material, but by its tensile strength, which becomes effective because of the tight adhesive connection of the cover sheet to the 85 filler. Substantially any sort of fabric, including delicate and expensive fabrics, may 90 100 105 110

be wound upon cloth boards so constructed without possibility of injury, and the boards are at the same time sufficiently strong to resist breakage or undue bending in shipment or transverse bending or breaking caused by the strain of winding the fabric, or shrinkage of the fabric after it is wound upon the board.

The accompanying drawing shows one representative structure embodying the invention and also sufficiently explains one way in which it can be economically produced. After considering this embodiment, persons skilled in the art will understand that many variations may be made, and I contemplate the employment of any structures that are properly within the scope of the appended claims.

Figure 1 is a perspective view of a cloth board embodying the invention in one form, different layers of the material being broken away for explanatory purposes.

Figure 2 sufficiently illustrates the production of such cloth boards by a continuous assembly method.

Figure 3 shows a complete cloth board produced by severing a piece from the continuous assembly of Figure 2.

In Figure 1 a filler or core structure is generally designated by reference letter F. This filler may consist of one or more sheets or layers of fibrous material such as cardboard, strawboard or the like, of suitable strength and stiffness. In the present example there are three filler sheets 1, 2 and 3, the different sheets or layers being preferably firmly secured together by adhesive sufficiently indicated by stippling. The complete core structure is enclosed in an envelope or cover C, which is preferably, although not necessarily, one integral sheet of fibrous sheet material. This may be almost any suitable fibrous sheet material of the class roughly designated as paper, but more specifically is, in preferred cases, of the same material or similar to the material which composes the filler, namely, strawboard or pulp-board of very substantial thickness, stiffness, and tensile strength, and in many cases the cover material is as thick or approximately as thick as the filler sheets; although, in some cases the cover material may be somewhat thinner, and also, if desired, it may be in some cases of a higher grade material, so long as it has sufficient thickness, stiffness and tensile strength.

The cover sheet is folded and adhesively secured about the filler, and the edges of the cover sheet are in most cases preferably arranged with meeting edges or a butt joint, as sufficiently indicated at 4, Figure 1, to avoid any unevenness in the surface of the paper. As or after the cover sheet is applied its longitudinal edges 5 are preferably formed or pressed to provide a smooth

and round contour, or at least the longitudinal corners 6 are so pressed or otherwise treated as to remove sharp edges and produce a generally round or smooth formation of these corners and the longitudinal edges 70 5. This edge formation enables the fabric to be wound smoothly and evenly on the cloth board without any sharp deflection of the fabric at the edges or corners of the board. The broad sides of the structure are smoothly and evenly surfaced by the envelope material and the finish of the external surface may be made as "high" or smooth and as decorative as may be desired by providing cover material of a suitable grade or material, which is smoothly surfaced or calendered, or else one surface of the cover sheet which is to be the external surface of the completed board may be covered with a sheet of highly finished paper.

When the filler consists of more than one layer of material the respective layers or plies are firmly secured together by adhesive, which preferably covers substantially the entire contacting surfaces, and similarly the cover sheet is secured to the filler by adhesive which covers substantially the entire contacting surfaces, so that the entire structure is firmly bound together, strengthened and reinforced by the adhesive; and the cover material, of substantial thickness, stiffness and tensile strength, greatly reinforces and strengthens the filler against torsional, transverse and longitudinal bending strains. This function of the cover sheet is substantially amplified by its tensile strength, which becomes effective for the stated purpose by reason of the firm and complete adhesive attachment of the cover to the filler, by reason of which practically all strains are distributed through the entire structure.

Other variations within the scope of the invention will be readily understood by skilled persons without detail explanation, and such variations are comprehended in the scope of the following claims.

Figure 2 sufficiently illustrates one approved method of producing cloth boards of this kind, this being what I call a continuous assembly method, in accordance with which the sheet or strip 1 of core material is advanced in continuous form, for instance, from a roll and the other sheets or strips 2 and 2 are similarly advanced and adhesive is applied as sufficiently indicated by stippling, to secure the core strips firmly together producing a continuous core assembly A. The sheet or web C of envelope material is also advanced in continuous form as from a roll. This sheet, as clearly shown in Figure 2, is much wider than the core strips. Adhesive may be applied to a surface of the cover web as suffi-

ciently indicated by stippling 7 or else the adhesive connection of the cover web may be provided for by adhesive on upper and lower surfaces respectively of the upper and lower filler strips. At a suitable point the cover web is folded over and adhesively secured to the broad upper and lower surfaces of the filler with the edges 4 of the envelope properly located, in this case being brought into abutting relation as explained in connection with Figure 1. There is thus produced, a continuous assembly B consisting of the core structure and the envelope applied as above described. At a suitable point in the formation of the assembly the edges 5 or corners 6 are pressed or otherwise treated to provide the rounded edge formations, sufficiently explained in connection with Figure 1. Individual cloth boards as shown in Figure 1 and also in Figure 3 are then produced by severing the continuous assembly transversely at suitable intervals. The assembly method described does not form a part of the present invention, but is disclosed and claimed in a companion application. The present cloth boards may be produced by other methods, but a preferred, economical method of production is here described to enable the structure of the board to be more fully understood and also to emphasize the low cost of the completed article, which is due not only to the low cost of the materials and the simplicity of the structure, but to the fact that it is capable of being produced by economical methods, such as the rapid and inexpensive continuous production methods referred to.

What I claim is:

1. A cloth board or similar article adapted for production by a continuous process in which the materials are advanced in continuous web form, brought together to form a continuous assembly, and severed transversely to produce the individual boards, said cloth board comprising a filler composed of fibrous pulp board of substantial thickness and stiffness, and an enveloping cover consisting of fibre board similar to the filler material and of substantial thickness, stiffness and tensile strength, the cover being adhesively secured to the filler substantially throughout the contacting surfaces and covering the broad surfaces and longitudinal edges of the filler, the entire surface of the board being smooth and free from sharp longitudinal corners and irregularities, and the cover substantially reinforcing and stiffening the filler against torsional, transverse and longitudinal bending strains, as well as providing a smooth board surface which will not damage fabrics wound thereon.

2. A cloth board or similar article adapted for production by a continuous process in

which the materials are advanced in continuous web form, brought together to form a continuous assembly, and severed transversely to produce the individual boards, said cloth board comprising a filler composed of a plurality of sheets of pulp board of substantial thickness and stiffness, adhesively secured together substantially throughout their contacting surfaces, and an enveloping cover consisting of fibre board similar to the filler material and of substantial thickness, stiffness and tensile strength, the cover being adhesively secured to the filler substantially throughout the contacting surfaces and covering the broad surfaces and longitudinal edges of the filler, the entire surface of the board being smooth and free from sharp longitudinal corners and irregularities, and the cover substantially reinforcing and stiffening the filler against torsional, transverse and longitudinal bending strains, as well as providing a smooth board surface which will not damage fabrics wound thereon.

3. A cloth board or similar article adapted for production by a continuous process in which the materials are advanced in continuous web form, brought together to form a continuous assembly, and severed transversely to produce the individual boards, said cloth board comprising a filler composed of pulp board of substantial thickness, stiffness and tensile strength, the cover being adhesively secured to the filler substantially throughout the contacting surfaces and covering the broad surfaces and longitudinal edges of the filler, the entire surface of the board being smooth and free from sharp longitudinal corners and irregularities, and the cover substantially reinforcing and stiffening the filler against torsional, transverse and longitudinal bending strains, as well as providing a smooth board surface which will not damage fabrics wound thereon, the longitudinal edges and corners of the envelope being rounded and smoothly finished to avoid injury to fabrics.

4. A cloth board or similar article adapted for production by a continuous process in which the materials are advanced in continuous web form, brought together to form a continuous assembly, and severed transversely to produce the individual boards, said cloth board comprising a filler composed of a plurality of sheet of pulp board of substantial thickness and stiffness, adhesively secured together substantially throughout their contacting surfaces, and an enveloping covering consisting of fibre board similar to the filler material and of substantial thickness, stiffness and tensile strength, the covering being adhesively secured to the filler substantially throughout the contacting surfaces and covering the broad surfaces and longitudinal edges of

the filler, the entire surface of the board being smooth and free from sharp longitudinal corners and irregularities, and the cover substantially reinforcing and stiffening the filler against torsional, transverse and longitudinal bending strains, as well as providing a smooth board surface which will not damage fabrics wound thereon, the lon-

gitudinal edges and corners of the envelope being rounded and smoothly finished to 10 avoid injury to fabrics.

Signed at Brooklyn, in the county of Kings and State of New York, this 5th day of Oct. A. D. 1923.

HARRY BRIDGMAN SMITH.
